(57) **CLAIM**

We claim the ornamental design for a light housing, substantially as shown and described.

DESCRIPTION

FIG. 1 is a perspective view of a light housing according to the present invention except that it illustrates in broken lines a water nozzle and general structure underneath the nozzle. It illustrates a general possible environmental use of the design. A mounting plate and diagrammatic illustration of lights inside the housing are also shown in broken lines.

FIG. 2 is a top plan view of FIG. 1.

FIG. 3 is a front elevation of FIG. 1. A rear elevation would be identical except the location of the electrical connecting cord would be reversed.

FIG. 4 is a right side elevation of FIG. 1. A left side elevation would be identical; and,

FIG. 5 is a bottom plan view of FIG. 1.

The broken lines shown in the drawings are for illustrative purposes only and form no part of the claimed design.
